tion, Ellenville, N.Y., a corporation of New York

Filed Aug. 15, 1963, Ser. No. 76,226

Term of patent 14 years

(Cl. D26—14)

FIG. 1

FIG. 2

FIG. 3

FIG. 4

FIG. 1 is a top plan view of an antenna array or similar article showing our new design;

FIG. 2 is an end elevational view to a reduced scale;

FIG. 3 is a side elevational view, the opposite side being substantially a mirror image thereof; and

FIG. 4 is an opposite end elevational view to an enlarged scale, the grid reflector being omitted for convenience in illustration.

A portion has been broken away and omitted in FIGS. 1 and 3 for convenience in illustration.

The dominant features of our new design are shown in solid lines in the drawing. The fragmentary showing of a supporting mast in dash-dot lines is for illustrative purposes only.

We claim:

The ornamental design for an antenna array or similar article, substantially as shown and described.
